UNITED STATES PATENT OFFICE.

ADA ADDISON, OF CINCINNATI, OHIO.

DESIGN FOR A CASING FOR FACE-STEAMERS.

SPECIFICATION forming part of Design No. 29,567, dated November 1, 1898.

Application filed October 1, 1898. Serial No. 692,446. Term of patent 3½ years.

To all whom it may concern:

Be it known that I, ADA ADDISON, a citizen of the United States, residing in the city of Cincinnati, Hamilton county, and State of Ohio, have invented and produced a new and original Design for a Casing for Face-Steamers, of which the following is a specification, reference being had to the accompanying drawing, forming part hereof.

5 The figure in the drawing is a view of the casing of a face-steamer showing my new design.

10 The distinguishing feature of my invention or design consists in the peculiar shape of the 15 casing for a face-steamer, the body describing an inverted cone shape, at the upper end of the cone-shaped body describing a bulbous head or distributor, and describing at the lower end a circular base.

20 The body A inclines from the base B to the rose or distributor C.

The base B is a plain cylinder. The body A,

which projects from it, is an inverted-cone shape, meeting the rose or distributor C, inclining at an angle from base B, while tapering toward its neck a.

The rose or distributor C has a neck b, tapering down from a bulbous body d to meet the tapering neck a of the body A, and when put together inclines at an angle to said body A. 25

The upper portion or cap D of the rose or distributor C is slightly dome-shaped and circular in contour, diverging into the large bulbous body d, and is united to this body by circular beaded moldings or rings E. 30

Having described my invention, what I claim as new, and desire to secure by Letters Patent, is—

The design for a casing for face-steamer as herein shown and described.

ADA ADDISON.
